FIG-5

FIG-7

FIG-8

FIG-10

FIG-11

FIG. 12

FIG. 13

FIG. 14

FIG. 15

FIG. 16

FIGURE 1 is a perspective view of an air-supported structure showing our new design;

FIGURES 2 and 3 are respectively top and end views of a square shaped, air-supported structure of the type shown in FIGURE 1;

FIGURES 4 and 5 are respectively top and end views of a rectangular air-supported structure of the general type shown in FIGURE 1;

FIGURES 6 and 7 are respectively top and end views of a rectangular air-supported structure showing a first alternate embodiment of our new design;

FIGURES 8 and 9 are respectively top and end views of a rectangular air-supported structure showing a second alternate embodiment of our new design;

FIGURES 10 and 11 are respectively top and end views of a rectangular air-supported structure showing a third alternate embodiment of our new design; and

FIGURES 12 through 16 are enlarged sectional views of a portion of the five embodiments of our new design, such enlargements show the top outer surface area of the

structure where its central, longitudinal, vertical plane intersects the structure at abutment zones of any two or more adjacent segments of the structure and the central band widens to form the geometric patterns shown in these figures. These five embodiments are substantially the same as those shown in FIGURES 1-11 except for these top outer surface areas.

We claim:

The ornamental design for an air-supported structure, as shown and described.
